CLAIM

The ornamental design for a silicone collapsible water bottle, as shown and described.

DESCRIPTION

FIG. 1 is a bottom, front and left side perspective view of a silicone collapsible water bottle showing my new design; FIG. 2 is a top, rear and left side perspective view thereof; FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a top, rear and left side perspective view showing the silicone collapsible water bottle in a stretched state.

The broken lines in the drawings illustrate portions of the silicone collapsible water bottle which form no part of the claimed design.
